UNITED STATES PATENT OFFICE.

JAMES D. WALSH, OF ST. LOUIS, MISSOURI.

HANGER FOR PICTURES, CARDBOARD, AND THE LIKE.

No. 823,379.

Specification of Letters Patent.

Patented June 12, 1906.

Application filed July 24, 1905. Serial No. 271,028.

To all whom it may concern:

Be it known that I, JAMES D. WALSH, a subject of the King of Great Britain, residing at St. Louis, State of Missouri, have invented 5 certain new and useful Improvements in Hangers for Pictures, Cardboard, and the Like, of which the following is a full, clear, and exact description, reference being had to the accompanying drawings, forming a part 10 hereof.

My invention has relation to improvements in hangers for unframed pictures, cardboard, mattings, and, in fact, any character of sheet material intended to be exposed to view; and 15 it consists in the novel construction of parts more fully set forth in the specification and pointed out in the claim.

In the drawings, Figure 1 is a front elevation showing the application of my invention. 20 Fig. 2 is an enlarged front elevation of the hanger, showing a cardboard gripped between its jaws. Fig. 3 is a vertical cross-section on line 3 3 of Fig. 2. Fig. 4 is a front elevation with locking-lever removed. Fig. 5 is 25 a perspective of the locking-lever detached, and Fig. 6 is a side view showing the jaws open and also in dotted position showing them partially closed and the position of the lever corresponding to such partially-closed position 30 of the jaws and showing also the supplemental hook coupled to the securing-prong of the hanger.

The object of my invention is to construct 35 a hook for the hanging of cardboard, pictures, and the like which may be attached either to a sheet of burlap or similar reticulated material or suspended from a rod, wire, or string; one which may accommodate variable thicknesses of board, and one possessing further 40 and other advantages better apparent from a detailed description of the invention, which is as follows:

Referring to the drawings, 1 1' represent, 45 respectively, the relative stationary and movable members or jaws of a clasp adapted to embrace the faces of the cardboard or sheet to be hung, the clasp being preferably made of a single sheet of metal folded at what constitutes the hinge-joint between the jaws, said 50 joint being resilient and normally tending to force the jaws apart. Formed with what constitutes the relatively stationary jaw and spanning the edges of the movable jaw 1' are brackets or arms 2, between whose free ends

is pivoted a locking-lever 3, the base of which 55 is formed into an eccentric or cam loop 4, having a milled surface, the ribs or serrations 5 thereof being disposed lengthwise of the loop or in a direction transverse to the lever. These serrations coöperate with a correspond- 60 ing series of serrations or ribs 5', formed on the movable jaw for a purpose presently to appear. Immediately above the serrations 5' the movable jaw has stamped therefrom a resilient tongue 6, between which and the 65 body of the jaw may be inserted and retained a price-card C. Stamped from the stationary jaw at a point below the hinge-joint is a rear- 70 wardly-depending prong 7, which may be inserted into the meshes of a suitable back- ground of burlap or equivalent reticulated sheet B, to which the hangers are attached. Should occasion require the attaching of the hanger to a wire, rod, or string S, the same 75 may be provided with a hook 8, the base of which is slipped or passed over the prong 7, as shown in Fig. 6. The free ends of the jaws 1 1' are provided with rubber tips, pads, or 80 cushions 9 for gripping the cardboard P, the soft material of which the tips are composed 85 insuring against scratching or similar de- destruction of the material of which the card- board may be composed.

When the jaws 1 1' are open, the locking- 90 lever hangs substantially parallel to the mov- able jaw 1'. Upon insertion of the picture P between the jaws the swinging of the lever upward forces the movable jaw toward the stationary jaw, thus gripping the picture be- 95 tween them, and when once securely gripped the lever remains in its locked position by reason of the frictional engagement between the serrated or milled surfaces 5 5'. The pur- 100 pose of making the loop 4 cam-shaped or ec- centric to the axis of oscillation of the locking- 105 lever is to enable the jaws to be forced into greater or less proximity toward one another, depending on the thickness of the material or board to be gripped between said jaws. The farther up the lever is swung the closer it will force the jaws together.

As above stated, the hanger proper, with the exception of the locking-lever, may be and preferably is made of a single sheet of metal, (or other material,) together with the 105 tongue 6 and prong 7. With the use of my hanger pictures may be handled indefi- 110 nitely without danger of deterioration or

leaving any mark where the same have been gripped between the cushioned jaws, as is obvious.

Having described my invention, what I claim is—

As an article of manufacture, a clasp made of a single sheet of metal and comprising a pair of normally open jaws connected by a resilient hinge-joint, a depending prong stamped from one of the jaws, an upwardly-projecting centrally-disposed tongue stamped from the opposite jaw, a pair of arms formed with the jaw carrying the prong and projecting forwardly and spanning the edges of the jaw

carrying the tongue, a locking-lever pivoted between the ends of the arms, and having a basal eccentric serrated loop for forcing the jaws together, the adjacent jaw having serrations for engaging the serrations of the loop, and cushioning tips or pads on the jaws, substantially as set forth.

In testimony whereof I affix my signature in presence of two witnesses.

JAMES D. WALSH.
